UNITED STATES PATENT OFFICE.

ELMER E. BARTON, OF WARRENSBURG, ILLINOIS.

DISPLAY-CABINET.

SPECIFICATION forming part of Letters Patent No. 781,759, dated February 7, 1905.

Application filed September 24, 1903. Serial No. 174,475.

To all whom it may concern:

Be it known that I, ELMER E. BARTON, a citizen of the United States, residing at Warrensburg, in the county of Macon and State of Illinois, have invented certain new and useful Improvements in Display-Cabinets; and I do declare the following to be a full, clear, and exact description of the invention, such as will enable others skilled in the art to which it applies to make and use the same.

This invention relates to an oil-cloth cabinet.

The object of the invention is to provide a device of this character whereby several designs and qualities of cloth may be exhibited and permitted of being reeled off for sale.

To this end the invention consists in certain features of construction and combination of parts, which will be hereinafter fully described, and particularly set forth in the appended claim.

In the accompanying drawings, Figure 1 is a perspective view of my improved machine. Fig. 2 is a longitudinal sectional view of the same. Fig. 3 is a section on line 3-3 of Fig. 2. Fig. 4 is a view of one form of cutter. Fig. 5 is a view of a different form of cutter. Fig. 6 is a view of still another form of cutter.

In the drawings the same reference characters indicate the same parts of the invention.

A denotes the cabinet, comprising the vertical standards 1, connected by the upper cross-piece 2 and the lower cross-piece 3. Journaled between these standards is the reel-frame 4, consisting of disk-heads 5 and longitudinal strips 6, connecting them. Arranged in the peripheries of these heads are screw-eyes 7 to serve as bearings for the reel-spindles 8, upon which the oil-cloth or other goods to be exhibited is placed. The axis of the reel-frame is provided with a crank 9, by means of which it may be rotated. Any number of these spindles may be mounted upon the reel-frame. As shown, each spindle 8 has a polygonal end 8' for engagement by a crank-wrench 9', which is adapted to be inserted through an opening in one of the standards 1 for winding the cloth from the original bolt onto the standard.

A take-up roll 10 is journaled in the side

pieces of the main frame and provided with a longitudinal slot 11, in which fits a hinged clamping-strip 12. This roll is provided with a crank 13, by means of which it may be rotated.

In the bottom of the cabinet is a sliding leaf 55 or shelf 10', which may be drawn out to support the detached portion of the cloth.

A fixed bar 14 is secured above the take-up roll. A longitudinally-slotted hinged bar 15, which is adapted to be adjusted by suitable finger-pieces 15', bears on said bar 14 and is locked in position thereon by a fastening 16. The bars 14 and 15 form a guide for the cloth feeding from the reel to the take-up roll, a brake to normally frictionally engage the moving cloth and hold the portion thereof on the take-up roll taut to prevent the feed of a surplus quantity of goods after the motion of the take-up roll has been arrested, and a catch for the end of the strip or portion of the cloth 70 which is to be severed from the bolt or roll. The bar 15 further acts as a guide member, on which the cutting device may move in a determined path to sever the goods in a straight line while the goods are held between the same 75 and the bar 14, the latter sustaining the goods while the knife is exerting its cut.

Different forms of cutters are designated 17, 18, and 19, respectively, as shown in Figs. 4, 5, and 6. The cutter 17 consists of a head-piece 17^a and a triangular-shaped cutter-blade 17^b, which is adapted to be moved in the slot in the bar 15 to sever the oil-cloth or material. The cutter 18 has a differently-shaped cutter-blade, which acts in the same manner as the cutter-blade 17^b. The cutter 19 is provided with rotary cutter-disks, which also work through the longitudinal slot in the hinged bar 15.

In operation when it is desired to reel off 90 a quantity of oil-cloth from any particular reel supported by the reel-frame the end of the fabric is placed in the longitudinal groove of the take-up roll, and the hinged strip 12 is then closed over the end of the fabric, thus 95 securely clamping it to the roll. The oil-cloth is now reeled off by rotating the take-up roll, and when the desired amount has been thus

wound upon the take-up roll the hinged bar 15 is swung over the stationary bar 14 and secured thereto. By moving the cutter from one end to the other of the hinged bar the 5 material may be severed from the bolt, and the severed end thereof will fall upon the leaf or shelf 10', on which it may be conveniently folded and wrapped. The circumference of the take-up roll being known and being, say, 10 one yard, it will be understood that when the said roll has been once rotated while the cloth is attached thereto a yard of the said cloth will be wound on the said roll, and hence the latter may be used for measuring purposes. 15 From the foregoing description, taken in connection with the accompanying drawings, the construction, operation, and advantages of my improved reel will be readily appreciated without requiring an extended explanation. 20 It will be seen that the device is simple, that its construction permits of its manufacture at a small cost, and that it is exceedingly well adapted for the purpose for which it is designed, and it will of course be understood 25 that various changes in the form, proportion, and the minor details of construction may be resorted to without departing from the principle or sacrificing any of the advantages of this invention.

Having thus fully described my invention, 30 what I claim, and desire to secure by Letters Patent, is—

In a display-cabinet, the combination of a frame or casing, a reel therein and provided with a plurality of spindles for supporting 35 bolts or rolls of cloth, a revoluble take-up roll provided with a clamp to engage and hold the free edge of a strip of cloth to be unwound from any one of the bolts or rolls, and a guide for the unwinding cloth arranged 40 between the take-up roll and reel in the path of movement of the unwinding cloth, said guide comprising bars adapted to engage opposite sides of the cloth to operate as a brake thereon to hold the portion of the take-up 45 roll taut, and one of the bars of said guide being provided with a guide-slot whereby a severing device may be moved along the same to sever the gaged and braked end of the strip from the bolt or roll, substantially as 50 described.

In testimony whereof I have hereunto set my hand in presence of two subscribing witnesses.

ELMER E. BARTON.
